Atty's

UNITED STATES PATENT OFFICE.

ROBERT L. ADAMS, OF LOS ANGELES, CALIFORNIA, ASSIGNOR TO (MRS.) M. J. BEEBE,
OF SAN BERNARDINO, CALIFORNIA.

COMBINATION RACK AND BED.

Application filed March 29, 1923. Serial No. 628,443.

To all whom it may concern:

Be it known that I, ROBERT L. ADAMS, a citizen of the United States, residing at Los Angeles, in the county of Los Angeles and State of California, have invented new and useful Improvements in a Combination Rack and Bed, of which the following is a specification.

My present invention being a combination rack and bed, adapted for use in connection with an automobile, or the like, it is a primary object of this invention to provide means which shall be suitable for use during camping trips, summer outings and the like, in which a convenient accommodation for luggage is needed during the day and adequate sleeping accommodations are needed during the night.

It is an object of this invention to provide means of the character referred to which shall utilize a running board to support one end of a cot or bed and to constitute virtually an extension or section thereof; and I prefer to connect my cot to the running board by means which shall be capable of serving alternatively as legs for the cot, when the same is to be used separately from the vehicle, or as supports for one end of the cot, or as supports for a luggage rack, which may comprise the end frame of the said cot or bed, adapted to support the outer or remote end of the same.

It is a further object of this invention to provide means whereby a shelter or enclosing canopy may extend from the body of an automobile to cover a cot or bed connected therewith or to cover a luggage rack formed from an end frame of said cot or bed; and novel tension means may be included.

Other objects of my invention will appear from the following description of a preferred embodiment thereof and the appended claims, taken in connection with the accompanying drawings, in which

Figure 1 is a plan view showing one mode of connecting a horizontal frame with a running board to form a bed.

Fig. 2 is a vertical section on line 2—2 of Figure 1.

Fig. 3 shows how the outer or remote end support or frame of the cot or bed may be employed as a luggage rack, and an alternative securing means therefor.

Fig. 4 is an elevational view from the direction of the arrow 4 of Figure 3.

Fig. 5 is a detail view showing how that form of securing means which is disclosed in Figures 3 and 4 may be alternatively employed as a leg for the separable section of the cot.

Figs. 6 and 7 show an alternative securing means hereinafter referred to in which a separable leg, distinct from the clamping element is employed.

Fig. 8 exhibits, upon an enlarged scale, a form of tensioning means which I may alternatively employ at one end of a cot of my improved design.

Referring in detail to the parts of that embodiment of my invention shown in Figures 1 and 2, 1 is a separable section of a cot or bed, having the side elements 2, preferably formed of separate sections connected by hinges 3, the mentioned side elements being connected in any suitable way, as by the angle irons 4 and 5 at the respective ends thereof, and any suitable means, such as the "spring" 6, being supported by the frame so formed.

At the inner end of the frame 1, any suitable means may be employed to connect the same with the running board R, or other fixed part of an automobile; and in the form of my invention shown in Figures 1 and 2, I employ, for this purpose, castings 7, each provided with a pair of apertures 8 and 9, placed at right angles to one another, the socket 8 being in each case arranged to extend vertically and thereby adapted to receive the pins 10 upon the inner end of the frame 1 and thereby support the same. To secure the castings 7 to the running board, any suitable means may be employed, and for this purpose I have shown a subsidiary frame consisting of the angle iron 11, extending longitudinally of the running board and secured to the castings 7, this angle iron being riveted or otherwise secured to the arms 12 and the diagonal braces 13, which are adapted to overlie the top of the running board and to cooperate with an elongated member 14, which may also be riveted to the casting 7 and which is shown as provided with a set screw 15, adapted to contact with the bottom of the running board, thereby completing a clamp.

In order to make it possible to support

the frame 1, by the insertion of the pins 10 in the alternative sockets 9, and independently of the running board, when this is desired, I find it advantageous to make not only the casting 7 but the member 14 sufficiently strong to support one end of the frame 1, one form of the construction and mode of use here referred to being illustrated in Figure 5, showing leg 14^a.

- 10 It will be understood that when the parts thus far described are arranged in the manner indicated, a portion of the running board to which my cot is secured may be regarded as an extension thereof; and that 15 end of the cot which is remote from the running board may be supported in any suitable manner. I do not, ordinarily, prefer to support the mentioned outer end of the cot by tension means extending to or from 20 the automobile. I find it advantageous to employ supporting means which may have the character of an end frame 16, which may comprise the legs 17 and the horizontal members 18, the latter being shown as connected by uprights 19; and I prefer to employ simple means, such as the casting 20, provided with sockets 21, to secure the outer end of the cot, provided with engaging means such as the pins 10' thereto.
- 25 In order to facilitate the use of the end frame 16 alternatively as the upright element of a luggage carrier, I find it advantageous to form the lower ends 22 of the legs 17 of such size and shape that they may fit securely within the sockets 8 of the casting 7 or 7^a (Figure 3) or 7^b (Figure 6) whenever the pins 10 of the frame 1 shall have been lifted therefrom, as in the preparation for breaking 30 of a camp and continuing of a journey.
- 35 It will be obvious that when the frame 16 shall have been secured in the manner described, the remaining parts of the cot and any bedding or other luggage may be retained thereby upon the running board during 40 the continuance of a journey or the return from a camping trip.

In order to provide a shelter to exclude rain or wind or sun, and to provide a degree of privacy, any suitable means may be employed to secure a canopy over a cot of the character described; and for this purpose I have suggested the employment of extensions 22^a, which may be provided with knobs or with eyes 23, to which I may secure the cords 24 of a canopy 25, or covering of any desired construction, the upper ends of the cords being optionally secured to the top or side of the automobile adjacent to which my cot may be used.

45 Although I have proposed to use the

elongated member 14 of that form of my device which is shown in Figure 2, and the corresponding member 14^a, of that form which is shown in Figures 3 and 5, as a leg by which one end of the separable portion of my cot may alternatively be supported when it is not to be connected with the automobile, it should be understood that I may employ alternatively the construction shown in Figures 6 and 7, in which the separable element 14^b of wood or other material, suitably shaped and provided with an aperture, may be secured by the thumb screw 15^b; and it will be obvious that instead of securing one end of a cot to the running board, I might alternatively secure one side of a cot thereto in such manner that the area of a running board, or a part thereof, shall supplement the area of a removable section of a cot and complete the same.

50 As illustrated in Figure 8, instead of permanently securing both of the end elements 4 and 5 to the side pieces 2 of a horizontal cot frame, I may adapt one or both of the end elements 4, 5 to move relatively thereto. For example, I may provide the fixed horizontal element 18^a of a bed end frame with the fixed eyes or hooks whose swaged securing heads appear also at 26 in Figure 4, and I may also provide, upon the movable horizontal element 5^a to which one end of the spring 6 is secured, the links 27, securing to these the lever-links 28 provided with hooked ends 29 adapted to engage the links 27, and 28, so connected that movements of the character indicated in dotted lines shall tension the spring 6 or any equivalent horizontal support.

55 While I have described above one preferred embodiment and various alternative embodiments of my invention, it will be understood that parts thereof might be independently employed, and that various further modifications might be made without departure from the spirit and scope thereof, as the same are indicated by the foregoing description and the following claims.

60 What I claim is:

1. In combination, a cot frame and means for securing said frame to a running board, said securing means being provided with a plurality of sockets for alternative use.
2. In combination, a cot frame and means for securing said frame to a running board, said securing means being provided with a plurality of sockets for alternative use and arranged at right angles one to another.

65 In testimony whereof I have signed my name to this specification.

ROBERT L. ADAMS.
